UNITED STATES PATENT OFFICE.

FRANK O. THOMAS, OF LA CROSSE, WISCONSIN.

SAFETY-RAZOR-BLADE STROPPER.

Application filed July 9, 1921. Serial No. 483,530.

To all whom it may concern:

Be it known that FRANK O. THOMAS, a citizen of the United States of America, residing at La Crosse, in the county of La Crosse and State of Wisconsin, has invented new and useful Improvements in Safety-Razor-Blade Stroppers, of which the following is a specification.

The object of the invention is to provide 10 a simple and efficient means for stropping a safety razor blade under conditions insuring the application of the blade to a strop of the ordinary form under conditions insuring the dressing of the edge of the blade 15 at the proper angle for effective use; and moreover to provide means in connection with a device of this kind whereby the blade is alternately reversed to avoid the necessity of effecting a reversal by the turning of the 20 hand of the operator; and more particularly to provide means whereby a draw edge may be imparted to the blade to correspond with that which is applied to a razor blade when manually stropped by a skilled operator; 25 and with these objects in view the invention consists in a construction and combination of parts of which a preferred embodiment is shown in the accompanying drawings, wherein:—

30 Figure 1 is a view of the strop showing it applied in the operative position to a strop.

Figure 2 is a plan view of the same showing in full and dotted lines respectively the 35 positions of the parts in making a stropping stroke in opposite directions.

Figure 3 is a longitudinal sectional view of the device.

40 Figure 4 is a reversed plan view in detail. Figure 5 is a view of the handle or grip detached.

Figure 6 is a detail view of the shank which carries the housing.

Figure 7 is a detail plan, and

45 Figure 8 is a detail side view of a portion of the device showing the blade holder locked to prevent oscillatory movement of the spindle thereof.

50 The device consists essentially of a blade holder 10 of which the spindle 11 is mounted in suitable bearings in a housing 12 carried by a shank 13, and mounted also in bearings in the housing and parallel with the spindle of the blade holder is a bearing roller 14 having a rubber or like frictional 55 surface which is operatively connected with

the spindle of the roller by means of the intermeshing gears 15 and 16. As the implement traverses the strop indicated at 17, alternating in opposite directions as in the usual operation of stropping, the contact of the bearing roller with the surface of the strop causes the reversal of the blade holder in correspondence with the motion ordinarily imparted to the razor blade manually 60 in the stropping operation.

Removably engaged with the shank of the apparatus is a grip or handle 18 having a socket portion 19 with inwardly directed lugs 20 for engaging the shank while the apparatus is in use and permitting of removal of the handle for compactness in storing when the device is not in use.

As will be understood the housing may be 70 of any desired construction preferably serving as a means of protecting the gearing by which reverse motion is communicated to the spindle of the blade holder, the function otherwise thereof being that of a mounting 75 for the spindles of the blade holder and the bearing roller, and in order to provide for imparting a draw edge to the razor blade which is being stropped this mounting is 80 preferably pivotally mounted upon the shank to which the grip or handle is attached, to provide for a limited oscillatory 85 or swinging movement of the mounting and hence of the spindles of the blade holder and bearing roller with relation to but in a plane parallel with the shank, the pivot being indicated at 21 and a limiting pin 22 being 90 arranged in an arcuate slot 23 to determine the extent of angular movement of the 95 mounting relative to the shank.

Therefore as the implement is moved with the bearing roller in contact with the surface of the strop, to cause the reversal of the blade holder, the mounting carrying the said blade holder and bearing roller receive an oscillatory or swinging movement in a plane 100 parallel with the path of movement of the shank, to present the edge of the razor blade which is indicated at 24 at an angle less than ninety degrees to the path of movement of the blade on the strop, to impart to 105 the blade edge a draw which is essential in producing a keen and effective edge on the blade.

When it is desired to use the stropper without the advantage of the oscillatory 110 movement of the blade holder, which is illustrated partly in Figure 2, the grip or

handle 18 which is slidingly mounted upon the shank 13 by means of the guides 20 may be moved inward to bring the abrupt transverse terminal shoulder 21 of said grip or handle into contact with the adjacent end of the housing 12 as shown in Figures 7 and 8.

Having described the invention, what is claimed as new and useful is:—

1. A razor blade stropping device having a shank, a reversible blade holder and bearing roller arranged in axial parallelism, a mounting carrying said blade holder and roller and pivotally mounted upon the shank for oscillatory movement transversely of the shank, and a grip or handle slidingly mounted on the shank and provided with

means for engaging and locking said mounting in a fixed position.

2. A razor blade stropping device having a shank, a reversible blade holder and bearing roller arranged in axial parallelism, a mounting carrying said blade holder and roller and pivotally mounted upon the shank for oscillatory movement transversely of the shank, and a grip or handle slidingly mounted upon the shank and having an abrupt inner end for engagement with said mounting to lock the latter against oscillatory movement.

In testimony whereof he affixes his signature.

FRANK O. THOMAS.
